UNITED STATES PATENT OFFICE.

ALLEN BEHR, OF BROOKLYN, NEW YORK.

SPORT SHOE.

Application filed May 13, 1927. Serial No. 191,069.

My invention relates to sport shoes and has a particular reference to shoes adapted for playing lawn tennis or similar games.

The object of my invention is to provide 5 shoes adapted to exercise a strong grip on the surface of the tennis court thereby preventing the slippage of the player's feet.

Ordinary sport or tennis shoes are usually 10 provided with corrugated surface which prevents to a certain extent the skidding or slippage of the player's feet when the latter must suddenly stop or change direction of his running. These corrugations, however, 15 wear out very quickly, leaving a smooth surface at the point of greatest pressure. When so worn out the shoes offer but little 20 resistance to the sliding. But even when new these corrugations, being shallow and with tapering sides, slide rather easily over a smooth surface.

In my shoes I provide a deep slot with square sides running across the whole width of the shoe and at the point of the greatest pressure, i. e., under the ball of the foot. In 25 order to prevent the collapse of the edges or sides of the slot I fill this slot with a cord or of a fibrous material. This fibrous material offers additional friction and supports 30 the working edges of the slot. On a clay court it gathers dirt thereby increasing the friction between the shoe and the ground.

My invention is more fully described in the accompanying specification and drawing in which—

35 Fig. 1 is a side elevation of my shoe partly in section, Fig. 2 is a bottom plan view of my shoe, and Fig. 3 is a partial sectional view of a modified construction.

40 My shoe 1 comprises a regular sole 2 made of leather or some fibrous material to which a layer of ordinary rubber 3 is cemented. To this layer is vulcanized a sole 4 made of a frictional corrugated or so called "crepe" rubber or of a similar elastic material. This 45 rubber has a rough surface which soon wears out smooth however, and in my shoe I do not depend on this surface for a frictional grip with the ground. For this purpose I provide a transverse slot 5 through the full 50 thickness of the layer of crepe 4. This slot does not reach the ends of the sole, leaving bridges 6. A piece of a fibrous cord 7 is placed in the slot 5 and is cemented or vulcanized to the bottom of this slot. The ends 55 of the cord 7 are wedged or compressed under the bridge members 6.

The slot 5 is placed at the point of the greatest pressure or directly under the ball of the foot, so that the full weight of the body is transmitted to the ground at the 60 point of this slot. These conditions remain unchanged even when the heel is raised from the ground as shown with dotted lines in Fig. 1.

In service the cord 7 becomes somewhat 65 flattened as it possesses much less resiliency than rubber and becomes depressed as shown in Fig. 3. This leaves a slot with working edges 8. The slot itself has a tendency to gather dirt thereby adding to the frictional 70 resistance of the shoe at this point. The cord 7 should be preferably made of a loose fibrous material, such as hemp or jute, twisted as shown in Fig. 2 so as to impart to it a certain mechanical strength. The 75 main object of this cord is to gather sand and dirt, scraped off the ground by the projecting edges of the slot 5, this sand or dirt adding to the frictional resistance of the sole. In order to facilitate this dirt gathering process the cord 7 is preferably not impregnated and is retained principally by its ends being wedged under the outer sole as shown in Figs. 1 and 2. For this purpose also it is desirable to provide the slots 5 80 deeper than the thickness of the cord 5, as shown in Fig. 3, so as to have from the beginning of the service of the shoes the exposed edges of the slot 5. These exposed edges provide a scraping effect on the ground 85 thereby providing an additional resistance to slipping or sliding of the shoes, and, secondly, scraping off dirt, as described, which then works its way between the fibers of the cord 7 increasing its frictional resist- 90 ance. In order to increase this gripping and scraping effect the edges of the slot 5 are made slightly diverging as shown in Fig. 3.

95 A second slot 9 with a second cord 10 may 100 be provided as shown in Figs. 1 and 2, adding to the effect of the first slot.

Fig. 3 shows a modification in which instead of a cord 7 a roll of rubberized cloth 11 is used. Any similar substance may be 105 used as a filling, provided it has less resiliency than rubber and has a tendency to gather dirt from the ground.

110 Important advantages of my shoe are that it provides an effective frictional resistance, increases the flexibility of the shoe at the point where it has a tendency to bend in

service and that it has a long life, the frictional properties of my feature not decreasing substantially until the sole is completely worn out.

5 I claim as my invention:

1. In a sport shoe, the combination with an elastic sole of a shoe, said sole being provided with elongated slots extending transversely across said sole, bridges at the ends of said slots, said slots extending under said bridges, and twisted cords of loose

fibrous material placed at the bottom of said slots, the ends of said cords extending under said bridges to the outer edges of said sole.

2. A sport shoe, the sole of said shoe being provided with elongated slots of an uniform width extending across said sole, bridges at the ends of said slots, the edges of said slots diverging outwards.

15 In testimony whereof I affix my signature.

20 ALLEN BEHR.
